Specification for Design.

Patented Jan. 2, 1917.

Application filed September 22, 1916. Serial No. 121,678. Term of patent 7 years.

To all whom it may concern:

Be it known that we, ROBERT Y. BARROWS and GEORGE V. STRAHAN, citizens of the United States, residing at Rutherford, in the county of Bergen, and Newark, in the county of Essex, both in the State of New Jersey, have invented a new, original, and ornamental Design for a Bowl for Lighting-Fixtures, of which the following is a specification, reference being had to the accompanying drawing, forming part thereof.

Figure 1 is a side elevation of an article

showing our new design. Fig. 2 is a fragmentary top plan view of the same. Fig. 3 is a fragmentary horizontal section thereof taken on line 3—3, Fig. 1.

We claim:

The ornamental design for a bowl for lighting fixtures, as shown.

ROBERT Y. BARROWS.
GEORGE V. STRAHAN.
